UNITED STATES PATENT OFFICE.

ALFREDO BUTTAFOCO, OF CHICAGO HEIGHTS, ILLINOIS.

WINDMILL.

1,144,932.

Specification of Letters Patent. Patented June 29, 1915.

Application filed January 15, 1915. Serial No. 2,383.

To all whom it may concern:

Be it known that I, ALFREDO BUTTAFOCO, citizen of Italy, residing at Chicago Heights, in the county of Cook and State of Illinois, have invented certain new and useful Improvements in Windmills; and I do hereby declare the following to be a full, clear, and exact description of the invention, such as will enable others skilled in the art to which it appertains to make and use the same.

This invention relates to toy wind mills, and one of the principal objects of the invention is to provide a toy which will simulate a convent or church in which certain figures are mounted to move and a bell is mounted to ring, the figures and bell being operated by means of a windmill at the side of the structure, thus providing a toy which will be amusing and instructive.

The foregoing and other objects may be attained by means of the construction illustrated in the accompanying drawings, in which—

Figure 1 is a front elevation of a toy wind mill made in accordance with this invention, Fig. 2 is a side elevation of the same, Fig. 3 is a detail view showing a number of figures mounted on a turn table to be operated by the wind mill, Fig. 4 is a detail view of a portion of the bell ringing mechanism, Fig. 5 is a detail view of the bell and its manner of mounting, and Fig. 6 is a detail view showing the figures to which the bell cord is connected.

Referring to the drawing, the numeral 1 designates a building preferably formed to simulate a church or convent mounted on supports 2 and provided with oppositely disposed windows 3, and circular openings 4 in the gable and the roof. The building is preferably provided with a tower 5 which is open at its opposite sides as at 6 and provided with a suitable window 7 one upon each side of the tower.

The numeral 8 designates the floor of the building.

A shaft 9 is mounted in a suitable bearing 10 connected to one of the walls of the building, and mounted on the shaft 9 is a wind wheel 11 provided with vanes or blades 12. The shaft 9 extends through the building parallel with the floor 8 and is provided with a beveled gear wheel 13 which meshes with a similar gear wheel 14 on a short vertical shaft 15. The shaft 15 is supported by means of an arm 16 connected to

a horizontal bar 17 which is supported upon a vertical standard 18 secured to the floor 8. Mounted rigidly upon the vertical shaft 15 is a turn table 19 comprising a plurality of arms extending radially from the shaft 15, and mounted upon each of said arms is a figure 20 preferably each representing a priest or other church dignitary. The shaft 15 is mounted at its upper end in an L-shaped support 21 connected at its upper end to a beam 22 suspended from the interior framework of the structure.

Mounted in the tower 5 is a bell 23, said bell being connected by means of a ring 24 to a vertical bar 25, said bar being secured to a cross rod 26 pivotally mounted at 27 in the sides of the tower. A curved bar 28 is connected to the upper end of the bar 25, and at the opposite ends of the bar 28, cords 29 and 30 are connected. The cord 30 leads to an articulated figure 31 mounted upon a support 32, and the cord 29 leads to a similar figure 33. Leading from the figures 31 and 33 are cords 34 and 35, said cords being connected to the figures in a manner to move them to ring the bell 23. The cord 34 is connected to a link 36 pivotally connected to a crank 37 mounted on the shaft 9. Connected to the cord 35 is an elastic band 38 secured at 39 to the wall of the building.

When the wind wheel 11 rotates, the figure 20 will move around the shaft 15 and can be seen through the windows 3, while the figures 31 and 33 will be seen through the windows 7 ringing the bell 23. The link 36 being pulled down by the crank 37 against the elasticity of the band 38 will ring the bell and move the figures 31 and 33 alternately.

From the foregoing it will be obvious that a toy made in accordance with this invention will be interesting to old and young and will be operated by placing the toy where the wind will strike the wheel 11.

Various changes may be made in the details of construction without departing from the spirit and scope of the invention as defined in the claims.

What is claimed is:—

1. A toy comprising a shaft, a wind wheel on said shaft, a turn table and connections between said shaft and turn table, a plurality of figures mounted on the turn table, a bell, and connecting mechanism for ringing the bell when the wind wheel is rotated.

2. A toy comprising a building having

open windows, through which moving figures can be seen, and through which a bell can be seen ringing, a shaft mounted in the building, a wind wheel mounted on the 5 shaft outside the building, a turn table, and connections between the shaft and turn table, a plurality of figures mounted to be carried by said turn table around the central point, a tower, a bell pivotally mounted 10 in said tower, cords leading from the bell to figures in the tower for ringing the bell, and connections between the wind wheel shaft and said figures.

3. A toy comprising a building having a 15 tower, a shaft mounted in the building and provided with a wind wheel outside the building, a crank on said shaft inside the building, a turn table, connections between said shaft and turn table, a series of figures 20 mounted on the turn table, a bell in the

tower, figures in the tower, a cord connected to the figures in the tower and to the bell and to said crank at one end and an elastic band connected to the other end of said cord and to the building.

4. A toy comprising a building to simulate a church having a tower thereon, a bell pivotally mounted in said tower, a turn table, a plurality of figures mounted on the turn table, a shaft, a wind wheel mounted 30 on the shaft for moving said figures, and means for actuating the bell, said building having openings therein to display the figures and the bell.

In testimony whereof I affix my signature 35 in presence of two witnesses.

ALFREDO BUTTAFOCO.
